(57) **CLAIM**

We claim the ornamental design for a biopsy pointer tool, as shown and described.

DESCRIPTION

FIG. 1 is a front perspective view of a pointer tool;

FIG. 2 is a front elevation view thereof;

FIG. 3 is a rear elevation view thereof;

FIG. 4 is a front plan view thereof;

FIG. 5 is a rear plan view thereof;

FIG. 6 is a left side elevation view thereof; and,

FIG. 7 is a right side elevation view thereof.

The broken lines are for illustrative purposes only and form no part of the claimed design.
